UNITED STATES PATENT OFFICE.

BENJAMIN FRANKLIN BURNETT, OF BROOKLYN, ASSIGNOR TO H. L. JUDD
& CO., OF NEW YORK, N. Y.

DESIGN FOR A MIRROR-FRAME, &c.

SPECIFICATION forming part of Design No. 20,136, dated September 9, 1890.

Application filed July 21, 1890. Serial No. 359,446. Term of patent 3½ years.

To all whom it may concern:

Be it known that I, BENJAMIN FRANKLIN BURNETT, of Brooklyn, Kings county, New York, have invented and produced a new and original Design for Frames, of which the following is a full, clear, and exact description, reference being had to the accompanying drawing, in which the figure is a face view of a frame bearing my new design.

10 The features of my invention are essentially the ornamentations *c*, alternating with the blocks or figures *b*, extending around the frame *A* and standard *B*, substantially as

shown, and of a second series of ornamentations *d*, running within the said series of ornamentations *c*, and blocks or figures *b*, and concentric therewith, the edge of said frame *A* having a scalloped appearance, substantially as shown. 15

I claim—

The design for frames, substantially as described.

BENJAMIN FRANKLIN BURNETT.
